2 SHEETS-SHEET 2.

BENJAMIN BRODO Inventor

By His Attorney *O.V. Thiele*

UNITED STATES PATENT OFFICE.

BENJAMIN BRODIO, OF NEW YORK, N. Y., ASSIGNOR TO THE SUPERHEATER COMPANY,
OF NEW YORK, N. Y., A CORPORATION OF DELAWARE.

SUPERHEATER.

1,411,680.

Specification of Letters Patent.

Patented Apr. 4, 1922.

Application filed February 16, 1921. Serial No. 445,501.

To all whom it may concern:

Be it known that I, BENJAMIN BRODIO, a citizen of the United States, and resident of New York, N. Y., have invented certain new and useful Improvements in Superheaters, whereof the following is a specification.

This invention relates to superheaters, and more particularly to the means employed for protecting such structures against excessive heat. It has for its principal object the provision of an improved form of such means and their arrangement with relation to the superheater. Other objects will be evident as the description proceeds.

In reading the following specification reference should be made to the accompanying drawings. In these drawings, Fig. 1 illustrates my invention in the form preferred when applied to a boiler of the general type appearing in that figure, Fig. 2 being a fragmentary sectional view on line 2—2 of Fig. 1; Fig. 3 shows a variation adapted to another form of boiler, Fig. 4 being a front view of a portion of the superheater elements, the protective means being in place; Figs. 5 and 6 are fragmentary views of two variations in the protective means; Fig. 7 is a section on line 7—7 of Fig. 1, on an enlarged scale.

It will become clear, before the description has proceeded very far, that the specific form of the boiler does not constitute an essential feature of my invention, although it may make advisable some modifications. It will also become clear just what essentials a boiler must have to make my invention applicable to it.

The boiler shown in Fig. 1 is one of an ordinary commercial form. Two upper drums 1—1 are connected to the two lower drums 2—2 by the tubes 3—3, the disposition being such that a combustion space 4 is left between the two sets of tubes, this space widening toward the bottom. The furnace space 5 is directly beneath this combustion space. An appropriate housing 6 encloses the boiler structure, while baffles 7 direct the products of combustion in several passes 50 along the tubes 3, as these products pass toward the stack connections 8—8.

This boiler structure and its function are well known and are not modified in any way for the present purpose.

55 The structure of the superheater proper

is also of a usual type. Headers 9—9 receive steam from the steam-and-water drums 1—1 by means of pipes 10—10, and deliver it to the superheater elements or units 11—11. These elements loop from the headers downward into the combustion space 4, and out again, connecting with their other ends to the central header 12. While no specific means of securing the elements to the headers are indicated in the drawings, I prefer to employ the familiar clamping means whereby one bolt holds the two ends of either the same or adjacent elements to the headers. This permits of ready detachment and reattachment when it is desired to remove elements for any purpose. The portion of the elements in the combustion space preferably includes two or three loops. All of the loops of any one element are arranged in a single plane and the several elements are arranged in parallel planes. This will appear clearly from Fig. 2. There are as many of these loops, and their spacing and size is such, as may be dictated in each case by such considerations as the amount of steam to be superheated, the temperature of the gases to be expected, the superheat it is desired to obtain.

The steam on its passage through these elements becomes superheated and is by them delivered to header 12, from which it is taken off by suitable connections (not indicated) and carried to the point of use.

The increased use of highly superheated steam has brought about the location of superheaters in positions such as above described. It will be evident that a location as exposed as this is to the extremely high furnace temperatures could be used without some form of protection only under the most favorable conditions. Where, e. g., steam consumption is intermittent, the engine or other steam-consuming device being shut down at times, the life of the elements would be seriously endangered unless they were shielded in some way from the direct furnace radiation. For this purpose I interpose a baffle 13 between the superheater and the furnace. This baffle I suspend entirely from the superheater elements. It is composed of a number of independent sections, some of which are lettered *a, b, c, d, e, f*, in Fig. 2. Each section is located under, and is suspended from, three elements. Each section abuts against, but is independent of its

neighbors. The means for suspending the sections from the elements are not a part of my invention, and any form preferred may be employed. I show, by way of illustration, hangers 14 for this purpose. I prefer to make the sections of fire-brick and to make them of the general construction indicated, but this is not essential; provided only they form a continuous baffle when in place and are independent of each other and secured only to the elements directly above them. In the form illustrated the baffle 13 is made up of upper bricks 25, suspended as clearly illustrated in Fig. 1, and lower bricks 26 whose method of suspension from the upper bricks will be evident from an inspection of Fig. 7.

The ends of the elements pass through the roof of the setting to reach the headers 9—9 and 12. The portion of the roof through which they pass should be made in sections readily removable and replaceable. The particular means used to accomplish this is not part of my present invention, and is of no particular interest here. All that is required is that when in place the roof shall be air-tight, and that it be readily removed and replaced in sections, as stated.

When now it is desired to remove an element, its connections and those of the two above the same baffle section with their header 9 and the header 12 are broken, whereupon the three elements together with the baffle section can be lowered into the furnace space and withdrawn through the furnace door. Replacing the elements and the baffle section is equally readily accomplished and the procedure will be evident. If the baffle 13 were a continuous structure, such as hitherto employed in analogous places, the difficulty and labor of such a removal and replacement are evident.

It will be clear that the sections must be closely enough in contact to present adequate obstruction to the intense furnace heat, but that no perfect closure is required.

The form of my device in Figs. 3 and 4 will be readily understood. The boiler has an upper drum 1^a and a lower drum 2^a, connected by water tubes 3^a. The furnace space 5^a is separated from drum 2^a by the wall W, and above the furnace space is the combustion space 4^a. The housing 6^a encloses the parts mentioned. Appropriate baffling directs the products of combustion from furnace 5^a and combustion space 4^a over the water tubes 3^a on their way to the stack connection 8^a.

The superheater headers 9 and 12 are here also arranged outside of the housing, and the elements or units 11 extend through the roof into the chamber 4^a. They are looped, and a baffle wall 13 is suspended from their lower ends, the baffle being made in sections wide enough to extend over the space below

three elements, just as in the case first described. These sections are also contiguous but independent and are suspended from the lower ends of the corresponding elements.

The protection for the superheater in this case is extended up on the front and rear, thus forming what may be called a housing for the superheater. The protection at the front and back takes the form of an apertured fire-brick wall, and is made up of 75 bricks corresponding in width to the sections of the baffle 13. Reference to Fig. 4 will make this clear. Bricks 15, each with a central aperture, 16, are arranged in tiers above the sections of baffle 13; each tier resting on the end of its section. Thus any one section of the baffle 13 and its two tiers of bricks 15 is removable independently of the adjoining portions of the protective structure. The tiers of bricks 15 will ordinarily 85 require no provision to keep them in place, but where such provision seems necessary or desirable they can be kept from falling outward in any desired way, e. g. by tie rods extending through the openings 16, or by a 90 band or bands extending entirely around the housing.

The openings 16 in the bricks are provided for the circulation of gases through the superheater space, and the radiation of 95 heat into it. Their size, shape and disposition may evidently be varied widely.

It will be clear that the advantageous features of the form first described are equally present here. When a unit of the superheater is to be removed, it is not necessary to remove the entire baffle protecting it, but the removal of the baffle section corresponding to it is sufficient. The unit, and the other two over the same baffle section with 105 it, are detached from the headers, whereupon the three units and the baffle section and bricks 15 can all be lowered into the furnace space and removed through the door.

I have shown three elements for each baffle section in both cases. Evidently this number may be varied, and the sections made narrower, to correspond to two elements, or made wider to correspond to more 115 than three.

In Fig. 5 are shown some superheater units with their suspended bottom protection, the latter illustrating the following variation: Instead of lying in the same 120 plane, alternate ones, 13^a, are suspended by longer hangers so that they lie in a plane below those, 13^b which are adjacent to the units. By this means most of the direct radiation from the furnace is intercepted, 125 but circulation of hot gases over the superheater is facilitated. Obviously the sets of units with their attached protective bricks can be independently removed here as in the cases first described.

Where it is desired to shut off the direct radiation a little more completely than in the variation just described, the bricks 13^a and 13^b may be made a little wider, as in 5 Fig. 6, so that the ends 18 and 19 do not clear. In that case, of course, some part of the ready removability is lost, as usually one lower set 13^a will have to be removed before it is possible to take out a set 13^b.

10 Other variations will naturally occur in practice.

What I claim is:

1. In a boiler having a furnace, the combination of superheater headers located 15 above said furnace, a plurality of aligned groups of tubular parallel superheater elements attached to the headers and arranged in proximity to the furnace, and a firebrick protective housing around the bottom, front 20 and rear of said superheater elements comprising a plurality of sections each corresponding to a group of elements and each supported entirely by its group independently of the other sections, whereby any 25 group and its housing section is removable and replaceable independently of the others.

2. In a boiler having a furnace, the combination of superheater headers, a plurality of aligned groups of tubular parallel superheater elements attached to the headers and a firebrick baffle below the superheater made 30 up of a plurality of sections each corresponding to a group of elements and each sus-

pended entirely from its group of elements independently of the other sections, whereby 35 any group and its section is removable and replaceable independently of the others.

3. In a boiler having a furnace, the combination of superheater headers, a plurality of groups of removable superheater elements 40 secured to the headers, means supported entirely by the elements to protect them against excessive heat, the means of each group being entirely separate from those adjoining, but contacting with them and with them 45 forming a continuous protection, whereby any one group with its protecting means may be removed and replaced without disturbing the others.

4. In a superheater structure, the combination of a plurality of aligned groups of tubular parallel superheater elements, and protecting means supported entirely by the elements, the means of each group contacting with those of neighboring groups but 50 55 being entirely separate from them.

5. In a superheater structure, the combination of a plurality of parallel aligned, relatively narrow removable superheater elements, means to protect them against heat 60 comprising a plurality of independent sections each attached to, suspended from, and removable with a relatively small number of these elements.

BENJAMIN BROIDO.
